UNITED STATES PATENT OFFICE.

ARCHIBALD WHITE, OF DUNBAR, PENNSYLVANIA.

PIPE-WRENCH.

1,312,290.

Specification of Letters Patent. Patented Aug. 5, 1919.

Application filed November 4, 1916. Serial No. 129,503.

To all whom it may concern:

Be it known that I, ARCHIBALD WHITE, a citizen of the United States, residing at Dunbar, in the county of Fayette and State 5 of Pennsylvania, have invented certain new and useful Improvements in Pipe-Wrenches, of which the following is a specification.

The present invention relates to tools and has particular reference to new and useful 10 improvements in pipe wrenches.

An object of my invention is to provide a novel, strong and durable yet cheaply constructed pipe wrench which may be quickly and easily applied to a pipe or other cylindrical object without the manipulation of 15 complicated adjusting elements.

A further object of my invention is to provide a wrench of the class described which is simple in construction, strong and 20 durable, cheap to manufacture and effective in operation.

Other objects and advantages to be derived from the use of my improved pipe wrench will appear from the following 25 detailed description and the claim, taken with an inspection of the accompanying drawing, in which:

Figure 1 is a side elevational view of a wrench embodying the improvements of my 30 invention, the same being shown applied in use;

Fig. 2 is a plan view of the same; and

Fig. 3 is an enlarged perspective of the gripping jaw removed.

Referring more particularly to the drawing, wherein similar characters of reference designate like and corresponding parts throughout the various views, 10 designates the handle or lever of my improved wrench, 25 the same preferably being formed with an enlarged end 12 bifurcated as at 13 to receive the pivot tongue 14 near the body portion of a gripping jaw designated 15 in its entirety.

The gripping jaw 15 at the upper part of its body portion is designed to form a head 16, said head being provided at its outer end and at a point beyond the tongue with a slot 17 to receive an object engaging flexible element such as a chain 18, one end of said chain being anchored to a pin 19 carried by the enlarged end of the lever 10 near the inner end of the bifurcation 13. The head 16 of the jaw 15 is formed with a 55 partition 20 through which said slot 17 is continued, recesses 21 being formed in the

partition adjacent the slot 17 to receive one of the links of the chain 18 as best shown in Fig. 1 at 22. A channel 23 is provided in the head 16 of the jaw 15 to accommodate the chain when necessary.

The head 16 is provided at its inner end above the tongue with an inwardly extending recess 25 the walls of which are inclined toward each other while the outer ends of 60 the walls form spaced gripping points or teeth 26 for engagement with the periphery of a pipe P or similar cylindrical element. As best shown in Fig. 1 the chain 18 is adapted to encircle the pipe P, one end of 65 the chain being engaged in the slot 17 by virtue of the recesses 21 engaging with the links of said chain. The jaw 15 is provided with shoulders 28 which are adapted to reinforce the same by virtue of their engagement with the edges of the enlarged portion 12 of the lever 10.

In use when the wrench is applied as shown movement is imparted to the lever 10 in the direction of the arrow, thereby tightening the chain about the pipe, and as the spaced gripping teeth 26 are respectively positioned between the point 19 and the pivot point of the jaw and between this latter point and the point of locking the chain 80 in the head, the chain will coöperate with the lever in exerting an equal simultaneous pressure on both of the teeth and cause them to engage and firmly hold the pipe to ultimately insure of the turning thereof, as is 85 apparent. The jaw does not move upon the pipe, thereby causing the chain to grip the pipe tighter and the pressure is increased.

From the above description taken in connection with the accompanying drawing, it 90 is thought that a clear and comprehensive understanding of the construction, operation and advantages of my invention may be had, and while I have shown and described the device as embodying a specific structure, 95 I desire that it be understood that such changes may be made in said structure as do not depart from the spirit and scope of the invention as claimed.

Having thus fully described my invention, what I claim as new and desire to secure by Letters Patent, is:—

A pipe wrench comprising a handle, a head pivotally connected with the forward end portion of the handle and extending 110 forward of and to one side of the handle, the forward portion of the head being cut to

provide a chain receiving pocket to receive and hold the free end of a chain, the side portion of the head being cut to provide a relatively deep pocket having its inner wall 5 extending longitudinally of the handle and its forward wall extending transversely of the handle, the head being provided with gripping teeth at the outer ends of the pocket walls, and a chain loosely connected

with the handle adjacent the head and intermediate the ends of the handle. 10

In testimony whereof, I affix my signature hereto.

ARCHIBALD ^{his}
mark X WHITE.
